THOMAS W. MCKENZIE, OF HAMMOND, BRITISH COLUMBIA, CANADA.

AUTOMATIC CIRCUIT-CLOSER.

949,593.

Specification of Letters Patent. Patented Feb. 15, 1910.

Application filed August 25, 1909. Serial No. 514,601.

To all whom it may concern:

Be it known that I, THOMAS W. MCKENZIE, citizen of the Dominion of Canada, residing at Hammond, in the Province of

British Columbia, Canada, have invented a new and useful Automatic Circuit-Closer, of which the following is a specification.

This invention relates to a circuit closer coöperated with the lever of a telegraph key and particularly designed to automatically close the circuit within a reasonable limit of time after an operator has ceased to use his key.

With an ordinary telegraph key the circuit requires to be manually opened and closed, and if the operator neglects to close the circuit after he has ceased to use the key, the circuit being open at that key, cannot be used by any other station and considerable difficulty is frequently experienced in locating the source of the trouble.

In the invention which is the subject of this application this inconvenience is guarded against by providing a telegraph key with a closing contact coöperative with it, that will maintain the circuit open while the key is being used but which, within a short time after the key ceases to be used, will automatically close the circuit. This is effected by providing a contact lever that is lifted off its contact while the key is in use, but that will gradually fall to close the contact when the key ceases to be used. This coöperative contact may be supplementary to the closing lever with which a telegraph key is usually provided, or the closing lever may be dispensed with and the automatic lever entirely relied upon as by it the circuit will be open while the key is in use, and will be automatically closed shortly after that use ceases.

Although the automatic closing device will effect this double purpose, the essential feature of the invention lies in the provision of a contact that will automatically close the circuit when the key is not in use.

The invention is particularly described in the following specification, reference being made to the drawings by which it is accompanied, in which:

Figure 1 is an elevation and part section view showing the supplementary contact with its resistance and the relation thereto of the operating extension from the key lever, Fig. 2, a plan of a telegraph key with its supplementary contact and Fig. 3, a

modified form of the key lever extension by which the supplementary contact is operated and the manner of connecting that contact in the circuit.

60

In these drawings 2 represents the lever of an ordinary telegraph key, 3 being its lever supporting frame secured to an insulated base 4.

The terminals of the external circuit 65 which form the binding posts of the key are represented by 5 and 8, and 7 represents the insulated contact of the key lever and 10 the contact lever that is at present used for closing the circuit when the key is not 70 in use. This closing contact lever 10 may be retained or not, but is not necessary to effect the closing of the circuit where my device is used as that closing is therein automatically effected.

75 Connections from the binding posts 5 and 8 of the external circuit are made respectively by connections 6 and 9 as at present, to the insulated contact 7 of the key, and to the metal base 3, and through it to its key 80 lever 2.

My invention consists in providing a means for closing the circuit between the terminals 7 and 8, that is coöperative with the key lever 2, and by introducing a means 85 for delaying this closing of the circuit so that it will not be effected until the lapse of a reasonable length of time after the key ceases to be used. This is accomplished by the provision of a pivotally mounted contact arm 13 that is in electrical connection with one side of the circuit, which contact arm normally rests upon a contact that is in electrical connection with the other side of the circuit, and by extending the key 90 lever as at 15 under this contact arm 13 that it will be lifted off its contact when the key is in use.

The fall of the contact arm 13 is delayed by providing a train of gear wheels 18, 19 100 with the teeth of the first wheel 18 of which a light spring or pawl 17 secured to the contact arm 13 is in engagement, so that the arm 13 being lifted by the extension 15 of the key lever when the key is depressed, 105 it will gradually fall to close the contact when that depression is released.

Figs. 1 and 2 show the contact arm 13 as in electrical connection with the terminal 8 of the external circuit, and the contact 110 arm normally rests upon a contact 11, as indicated by the dot and dash lines in Fig.

1, in connection with the other terminal of the circuit.

With this arrangement insulation 16 should be furnished on the key lever extension 15 to prevent the current passing through it.

Fig. 3 shows a modification, more readily applicable to an existing key, where the contact arm is electrically connected with 10 the terminal 5 and normally rests upon and in electrical connection with the extension 15 of the key lever, so that the circuit is closed by connection through the contact arm 13, the extension 15 of the key lever and 15 through the lever and its supporting base 3 to the other terminal 8 of the circuit.

In use, assuming the contact closing lever 10 to be opened or dispensed with entirely, the circuit being normally closed by the 20 contact arm 13 resting upon its contact 11, as in Figs. 1 and 2, or upon the key lever extension 15 direct as in Fig. 3.

While the key is in use the contact arm 13 is lifted off its contact to the position indicated by full lines in Fig. 1, which exaggerates the movement, in which lifting movement its pawl 17 will pass freely over the teeth of the gear or over finer ratchet teeth on a wheel introduced for the purpose if 30 thought necessary, and when lifted the ratchet will prevent it falling freely but it will be obliged to carry with it the first wheel 18 and rotate the train of gears so that its fall will be delayed. This delay 35 will hold the circuit open for a limited time after the key ceases to be used but thereafter the contact arm will eventually rest upon its normal support and will close the circuit.

The time of the fall may be varied by the 40 introduction of a balance wheel and escapement 20 in the train of gears or by the provision of a heavy headed screw 14 movable in or out in the free end of the contact arm 13, or by both.

45 Having now particularly described my invention, and explained the manner of its

use, I hereby declare that what I claim as new and desire to be protected by Letters Patent, is:

1. The combination with a telegraph key, 50 of an automatic circuit closer connected in circuit with the telegraph key and mounted independent of the key, said circuit closer having a movable contact member and said key having a projection to engage said contact member to move it in one direction as the key is depressed.

2. A means for electrically closing a telegraph circuit when the operating key is not in use, said means comprising a supplemental contact arm, a contact upon which said arm normally rests to close the circuit, means coöperative with the key lever for lifting the contact arm off its contact when the key is depressed, and means for 65 delaying the fall of the arm upon its contact.

3. A means for closing an electric telegraph circuit when the key is not in use comprising a pivotally mounted contact arm, 70 a contact upon which said arm normally rests to close the circuit, an extension from the key lever passing under the pivotally mounted arm to lift it off its contact when the key is depressed, and a train of gears co-operative with the contact arm that will not interfere with the lifting of the contact arm 75 but will delay its fall.

4. The combination with a telegraph key, 80 of a normally closed circuit controlling switch independent of the key, and means carried by the key to engage said switch to open said circuit when the key is depressed, and means for closing said switch a predetermined time after the key is released. 85

In testimony whereof I have signed my name to this specification in the presence of two subscribing witnesses.

THOMAS W. MCKENZIE.
